[57] CLAIM

The ornamental design for a combined bottle opener and recapper, as shown and described.

DESCRIPTION

FIG. 1 is a perspective view of a combined bottle opener and recapper showing my new design;

FIG. 2 is a front elevational view thereof;

FIG. 3 is a cross-sectional view taken along line 3—3 of FIG. 2; and

FIG. 4 is a right side elevational view thereof.

The rear of the combined bottle opener and recapper is plain and unornamented.
